UNITED STATES PATENT OFFICE.

JAMES FOSTER KING, OF NEW YORK, N. Y.

WIRELESS TELEGRAPHY.

SPECIFICATION forming part of Letters Patent No. 729,497, dated May 26, 1903.

Original application filed February 5, 1902, Serial No. 92,695. Divided and this application filed July 23, 1902. Serial No. 116,676. (No model.)

To all whom it may concern:

Be it known that I, JAMES FOSTER KING, a citizen of the United States, residing at New York, in the county of New York and State of New York, have invented certain new and useful Improvements in Wireless Telegraphy; and I do hereby declare the following to be a full, clear, and exact description of the invention, such as will enable others skilled in the art to which it appertains to make and use the same.

My present invention relates to improvements in wireless telegraphy, and more especially to an improved form of receiving apparatus for the same, and embodies, among other things, an improved coherer and combined decoherer and induction-coil.

My invention consists also in operating the receiving-relay usually employed in such systems upon a secondary circuit having current induced in it from the coherer-circuit, as contradistinguished from the ordinary practice of operating the relay in the coherer-circuit direct.

My invention consists, further, in improving the efficiency of the coherer-particles by making each of magnetic metal thinly covered with a metal envelop or coating which is both non-magnetic and non-oxidizable.

The apparatus embodying my present invention is shown and described in an application filed by me February 5, 1902, and serially numbered 92,695, of which the present application constitutes a division.

In order to more fully describe my invention, reference will be had to the accompanying drawings, in which—

Figure 1 is a diagram representing the receiving apparatus embodying my invention, and Fig. 2 represents inside elevation and partly in central vertical section the coherer and combined decoherer and induction-coil.

Similar letters refer to similar parts throughout both views.

The receiving apparatus comprises a coherer and combined decoherer A, double-contact relay B, and sounder C. This coherer comprises, among other parts, a glass-sealed tube a, in which is carried two silver plates a' a'', having preferably flat upper surfaces separated longitudinally by insulation a³.

These plates are provided, respectively, with the platinum-wire terminals a⁴ a⁵, which are fused in the tube. On the upper surfaces of these plates are placed the metallic particles a⁶, which form the coherer resistance. Though these particles may be of the ordinary kind used in coherers, I preferably employ a novel form, consisting each of a magnetic core—iron, for example—surrounded by or enveloped in a very thin non-magnetic and non-oxidizable covering, such as platinum. By thus providing the iron core with such a covering the particle is preserved against the destructive action of sparks. Moreover, on account of the very low resistance of the platinum and its non-oxidizable property better contact is formed and more current flows through the coherer than would otherwise be the case. Oxidation of the parts inside the coherer is further prevented by exhausting the air from the tube. The top of the coherer-tube is secured fast to a magnet pole-piece a⁷, which is in turn secured to the iron core a⁸ of an induction-coil. A thick copper-plated iron casing a⁹ supports the induction-coil and surrounds the coherer and protects it from local influences. The coherer-terminal a⁴ connects to the aerial wire a¹⁰, which passes through and is insulated from the core a⁸ and terminates in the sphere a¹¹ or its equivalent. The other coherer-terminal a⁵ makes connection with the metal casing a⁹, which may be connected to earth if desired.

In contradistinction to other systems I work the receiving-relay B upon a secondary or induced circuit. This circuit is the secondary a¹² of the coherer induction-coil, which is preferably of fine German-silver-wire, wound to about the same resistance as the coils of the relay. The primary a¹³ of this induction-coil is connected in series with the coherer-plates, coherer-battery E, choking-coil F, and part of the aerial circuit. The connection from the primary to the coherer-terminal a⁵ is shown as made through the metal casing a⁹. The primary and secondary coils of this induction-coil are mounted on suitable bobbins of insulation slipped over the core and inclosed in a suitable casing a¹⁴, as shown in Fig. 2. The self-induction of the choking-

coil F must be sufficient to damp out all the waves that tend to pass through it, and hence through the battery E and the primary of the coherer induction-coil.

5 The messages are received by oscillations striking the sphere a^{11} , connected to the aerial wire, causing the coherer-particles to cohere, and thus complete the circuit of the battery E. This induces a current in the secondary of the coherer induction-coil connected to the relay B and at the same time energizes the magnet pole-piece, which raises the particles from the plates and causes them to decohere. This induced current, however, will not alone energize the magnet of the relay B sufficiently to cause the said magnet to attract its tongue, nor is the current from the battery D alone sufficient to operate the said relay; but the combined action of the battery and the induced current, when both are acting in the same direction, will be sufficient to operate the said relay. Each time this relay is thus operated it completes, through its tongue and contact, the local circuit of the sounder C. Moreover, while the primary or magnetic circuit of said induction-coil will respond to each individual received impulse the secondary circuit of said coil will respond only to major or principal vibrations.

30 Having thus described my invention, it is obvious that the same may be modified without departure from the spirit thereof; but

What I claim, and desire to secure by Letters Patent of the United States, is—

35 1. In receiving apparatus for wireless telegraphs, a coherer, and a combined magnetic decoherer and induction-coil, the primary of said induction-coil comprising the exciting-coil of said decoherer.

40 2. A receiver for wireless telegraphs, comprising a coherer, a combined magnetic decoherer and induction-coil, and a local receiving-circuit, the said induction-coil acting both to excite the magnet of said decoherer and to induce current in the said receiving-circuit, from the coherer-circuit.

45 3. In receiving apparatus for wireless telegraphy, a coherer, a decoherer-magnet, an induction-coil wound on said magnet, the primary circuit of said induction-coil comprising the main coherer battery-circuit and the exciting-coil for the decoherer, and local receiving apparatus operated by the secondary circuit of said induction-coil.

50 4. In receiving apparatus for wireless telegraphy, an aerial circuit, a main coherer battery-circuit forming a branch of said aerial circuit, a magnetic decoherer, an induction-coil wound on said magnet, the primary of said induction-coil comprising the exciting-coil for said decoherer-magnet and the battery-circuit of said coherer, and local receiving apparatus connected in the secondary circuit of said induction-coil.

55 5. In a receiver for wireless telegraphs, the combination with a main aerial circuit, of a

coherer connected therein and comprising a glass tube inclosing metal plates insulated from each other, and cohering means for establishing electrical connection from one of said plates to another, of a decoherer-magnet pole-piece to which said coherer-tube is secured, a magnet-core secured to said pole-piece, an induction-coil wound on said core, the primary circuit of said induction-coil comprising the main coherer battery-circuit and the exciting-coil of said decoherer-magnet, and local receiving apparatus connected in the secondary circuit of said induction-coil.

60 6. In receiving apparatus for wireless telegraphy, an aerial circuit, a main coherer battery-circuit forming a branch of said aerial circuit, a choking-coil connected in said branch circuit, a magnetic decoherer, an induction-coil wound on said magnet, the primary of said induction-coil comprising the exciting-coil for said decoherer-magnet and the battery-circuit of said coherer, and local receiving apparatus connected in the secondary circuit of said induction-coil.

65 7. In receiving apparatus for wireless telegraphy, a continuously-closed local receiving-circuit connected to a source of electricity, a receiving-instrument normally excited by the current in said circuit but non-responsive thereto, and means operating upon the reception of a signal to increase the exciting-current of said instrument and to thereby render the same responsive to said signal.

70 8. In receiving apparatus for wireless telegraphy, a local receiving-circuit connected to a source of electricity, a receiving-instrument normally excited by the current in said circuit but non-responsive thereto, and means operating upon the reception of a signal independently of the ohmic resistance of the said local receiving-circuit to increase the exciting-current of said instrument and to thereby render the same responsive to said signal.

75 9. In receiving apparatus for wireless-telegraph systems; a local receiving-circuit; a source of electricity connected thereto; receiving apparatus operated by said circuit, non-responsive to the normal current therein, but responsive to said current when augmented; a second source of electricity, and a receiver of electrical oscillations adapted to augment the exciting-current of said circuit by current from said second source, upon the reception of a signal.

80 10. In receiving apparatus for wireless telegraphy, a local receiving-circuit and a source of electricity normally connected therein, an induction-coil, the secondary circuit of which forms a part of the said local receiving-circuit, a receiver of electrical oscillations operating said induction-coil and causing it upon the reception of a signal, to augment the electromotive force of said local circuit, and a local receiving-instrument connected in said local receiving-circuit, non-responsive to the normal electromotive force thereof but re-

sponsive to the augmented electromotive force.

11. In-receiving apparatus for wireless telegraphy, the combination with a coherer, of an induction-coil, the primary of which comprises the coherer battery-circuit, a local normally closed receiving-circuit including the secondary of said induction-coil, a receiving instrument and a source of electricity connected in said local circuit, the said receiving instrument being non-responsive to the normal electromotive force of said local circuit but only to the electromotive force augmented by induction from said induction-coil.
- 15 12. A receiver for wireless-telegraph systems, comprising a coherer, and a combined decoherer and induction-coil, the magnetic circuit of said induction-coil being capable of responding to each individual received impulse while the secondary of said induction-

coil responds only to major or principal vibrations.

13. A coherer particle for receivers of electrical oscillations consisting of a magnetic metal covered with another metal which is 25 non-oxidizable.
14. A coherer particle for receivers of electrical oscillations, consisting of magnetic metal covered with a metal which is both non-magnetic and non-oxidizable.

15. A coherer particle for receivers of electrical oscillations, consisting of iron covered with platinum.

In testimony whereof I affix my signature in presence of two witnesses.
